EDWARD H. WRAY AND WILLIAM J. HAGMAN, OF PHILADELPHIA, PENNSYLVANIA,
ASSIGNORS TO NILES-BEMENT-POND COMPANY, OF JERSEY CITY, NEW JERSEY.

HAMMER-PRESS.

1,084,054.

Specification of Letters Patent. Patented Jan. 13, 1914.

Application filed August 8, 1912. Serial No. 713,991.

To all whom it may concern:

Be it known that we, EDWARD H. WRAY and WILLIAM J. HAGMAN, citizens of the United States, residing at Philadelphia, 5 Philadelphia county, Pennsylvania, have invented certain new and useful Improvements in Hammer-Presses, of which the following is a specification.

This invention pertains to improvements 10 in that class of forging machines involving a hammer, actuated by steam or other elastic fluid, for striking impactive blows upon the work, together with a hydraulic press arranged to produce powerful squeezing 15 pressure upon the work.

The present invention will be readily understood from the following description taken in connection with the accompanying drawing which is a vertical section through 20 the hammer and press cylinders of a hammer-press exemplifying our invention.

In the drawing: 1, indicates a portion of the frame of the hammer-press, which frame may be of the character usual in machines 25 of this class of steam-hammers: 2, the cylinder of the steam-hammer, the term steam being used as typical of any suitable elastic fluid for operating the hammer: 3, the steam-chest, connected by ports with the upper and lower ends of the steam-cylinder 30 as usual in steam-hammers: 4, a valve, adapted to be operated as usual in steam hammers, the valve serving to admit steam to and exhaust it from either end of the 35 steam-cylinder: 5, the steam-inlet to the steam-chest: 6, the exhaust-outlet from the steam-chest: 7, the steam-piston working in the steam-cylinder: 8, the steam piston-rod, 40 9, the hammer-head carried by the lower end of the steam-piston-rod and adapted to slide in vertical guideways as is usual in steam-hammers: 10, the hammer-die secured as usual to the hammer-head: 11, the anvil 45 with which the steam-hammer co-operates: 12, a hydraulic press-cylinder disposed vertically alongside the steam-cylinder: 13, a water inlet connection to the upper end of the hydraulic-cylinder, this water inlet connection being adapted for communication 50 through suitable controlling valves with the source of supply of water which is to operate the hydraulic-press: 14, the hydraulic-piston working in the hydraulic cylinder:

15, the hydraulic piston-rod: 16, the hydraulic press-head carried by the lower end 55 of the hydraulic piston-rod, and adapted to slide in suitable vertical guideways: 17, the hydraulic press-die secured to the hydraulic press-head and co-operating with the anvil 11; and 18, a conduit leading to the lower 60 end of the hydraulic cylinder from the source of steam supply, the illustration showing this conduit as receiving its steam from the steam-supply connection to the steam-chest. 65

Under the control of valve 4 the steam-hammer may be operated as usual in steam-hammers, and at the same time steam entering the base of the hydraulic cylinder through conduit 18 exerts a constantly upward pressure on the hydraulic piston and maintains the hydraulic press-head and its die in elevated position. If water, at comparatively low pressure be admitted above the hydraulic piston, through connection 13, 70 the hydraulic piston and press-head will be moved down into contact with the work, the downward movement of the hydraulic piston displacing steam under the piston and forcing it back into the steam main or source 75 of steam supply. When the hydraulic die has made contact with the work then, through the connection 13, water at high pressure may be admitted to the hydraulic piston, thus forcing the hydraulic-head and 80 die down upon the work with enormous pressure and producing upon the work a squeezing action of high importance in certain classes of forging work. In some uses 85 of hammer-presses the descending movement 90 as well as the squeezing pressure of the hydraulic-die is produced by water at heavy pressure, as produced, for instance, by an accumulator and in this case the steam acting under the hydraulic piston need not be 95 exhausted but may find its way back to the source of steam supply. In other uses of hydraulic presses the lowering motion of the hydraulic-die is effected by water at comparatively 100 low pressure, the ultimate squeezing action being later produced by water at high pressure as from an intensifier. Our present invention lends itself to either system for the operation of hammer-presses. 105

A piece of work to be operated upon, hav-

ing been suitably heated, is laid upon the anvil, which anvil is common to the hammer-die and the hydraulic press-die. Then by suitably shifting the work upon the anvil it may be subjected to either the impactive blows of the steam-hammer or to the squeezing action of the hydraulic press, and the work in thus being subjected to action by the alternative instrumentalities 5 may be placed alternately under the dies, or the work of either die may be concentrated upon it to the exclusion of the other die. When hammering is to be done it is practicable to locate the work and then employ 10 the press to clamp it firmly for a period, and when pressing is to be done the hammer may serve in holding the work, and when the hammer is in use without the aid of the press the press-die is held up out of the 15 way, and when pressing is done, without the aid of the hammer, the hammer is held up out of the way.

In forging with steam hammers or combined hammers and presses, the pieces are 20 often of great weight, weighing many hundreds of pounds and require to be supported by a crane and to be worked promptly while at the proper high heat. In operating on a given piece while at proper forging 25 heat, some of the work calls for the impactive blows of the hammer and other work for the powerful squeeze of the press, and the shifting from one action to the other must be done with quickness and the work 30 must be accurately and firmly held. In the present device where the squeezing press and the striking hammer work on practically 35 the same anvil, the work may be presented

to the hammer or press as needed or to both successively.

40

We claim:—

1. A hammer-press comprising, a vertical steam-cylinder, a vertical hydraulic cylinder alongside the same, a piston in each cylinder, a piston-rod connected with each piston, a head carried by each piston-rod, a die carried by each head, an anvil below the dies, means for supporting the hydraulic piston in its upward position, a steam-valve controlling passages for the flow of steam 45 to and from above and below the steam-piston, and a conduit for admitting liquid under pressure above the hydraulic piston, combined substantially as set forth.

2. A hammer-press comprising, a vertical 50 steam-cylinder, a vertical hydraulic cylinder alongside the same, a piston in each cylinder, a piston-rod connected with each piston, a head carried by each piston-rod, a die carried by each head, an anvil below the 55 dies, a steam-valve controlling passages for the flow of steam to and from above and below the steam-piston, a conduit for admitting liquid under pressure above the hydraulic piston, and a conduit connected with 60 the base of the hydraulic cylinder and adapted to apply a pressure of steam below the hydraulic piston for the purpose of raising or holding the hydraulic piston in elevated position, combined substantially as 65 set forth.
